FOUNDATION GARMENT

Mario Laguzzi, Long Island City, N.Y., assignor to Poirette Corsets, Inc., New York, N.Y.

Original design application Jan. 31, 1962, Ser. No.
68,594. Divided and this application July 11, 1962,
Ser. No. 70,877

Term of patent 14 years

(Cl. D20—2)

FIG. 1

FIG. 2 is a rear elevational view thereof with part of the brassiere portion being shown broken away for convenience of illustration.

This application comprises a division of my copending application entitled Foundation Garment, Ser. No. D. 68,594, filed January 31, 1962.

I claim:

The ornamental design for a foundation garment, as shown and described.
